UNITED STATES PATENT OFFICE.

ALCID OSCAR WIEGANT, OF WATHENA, KANSAS.

MECHANICAL MOVEMENT.

No. 872,875.

Specification of Letters Patent.

Patented Dec. 3, 1907.

Application filed April 23, 1907. Serial No. 369,853.

To all whom it may concern:

Be it known that I, ALCID OSCAR WIEGANT, a citizen of the United States, and a resident of Wathena, in the county of Doniphan and State of Kansas, have invented a new and Improved Mechanical Movement, of which the following is a full, clear, and exact description.

The purpose of this invention is to provide novel features of construction for a mechanical movement, which are exceedingly simple and compact, that are adapted for converting rotary motion given to a horizontal shaft into vertical reciprocating and partial rotary motion for an upright driven shaft.

The improvement is applicable for the operation of different machines with equal facility; as, for example, a dough kneader, a butter worker, an egg beater, a meat chopper, a churn or a washing machine, and for the purpose of illustrating the improvement as applied, it is shown in connection with a washing machine of the pneumatic dasher type.

The invention consists in the novel construction and combination of parts, as is hereinafter described and defined in the appended claims.

Reference is to be had to the accompanying drawings forming a part of this specification, in which similar characters of reference indicate corresponding parts in all the views.

Figure 1 is a sectional side view of a washing machine of the type hereinbefore mentioned, and a side elevation of the improved mechanical movement combined therewith for its operation. Fig. 2 is an enlarged transverse partly sectional view of details of the improvement, substantially on the line 2—2 in Fig. 1, and Fig. 3 is a sectional plan view taken substantially on the line 3—3 in Fig. 2.

The washing machine shown comprises a suds box A, which may be formed either rectangular or circular in its side wall, having legs A' and a removable lid A².

As represented, the novel mechanical movement embodies a frame, preferably having two arms 5, 5^a joined together and upon a base flange 5^b. The arm 5^a curves forwardly and joins an upright frame member 5^c which, near its ends, curves forwardly producing a foot portion 5^d and a top portion 5^e.

The base flange 5^b and foot portion 5^d are seated upon and secured to the lid A² of the

suds box and support the other portions of the frame in a vertical plane. On the upper end of the arm 5, a box a is formed, and in the same horizontal plane therewith a similar box b is formed on the upright frame member 5^c. A shaft 6 is loosely mounted in the boxes a, b and on the end of said shaft which projects outward through the box a, a balance wheel 7 is mounted, having a crank handle 7^a thereon. On the opposite end of the shaft 6, a bevel pinion 8 is mounted and secured at a point near the upright frame member 5^c.

Upon the foot 5^d and top portion 5^e of the frame, an oblong ring member 5^g is secured by its ends respectively, said ring member that is disposed transversely of the frame a short distance forward of the frame member 5^c, loosely receiving the bevel pinion 8, between its spaced upright portions.

Forwardly of and near the upper end of the ring member 5^g, a vertically bored box c is formed on the end of the top frame member 5^e, wherein the upper end of a guide shaft 9 is secured as indicated in Fig. 2, said shaft projecting downward in a vertical plane.

A tubular plunger barrel 10 is loosely mounted upon the guide shaft 9 and passes loosely down through a perforation in the foot piece 5^d. Upon the barrel 10, near its upper end, a hub d of cylindrical form is preferably secured, but may be made integral with the barrel. From the elongated body of the hub d, three short arms d¹ project in the same vertical plane, and upon said arms similar roller-like teeth d² are rotatably mounted. The barrel-shaped roller teeth d² have such a relative position that they will mesh with the teeth of the pinion 8 at one side thereof, as shown in the drawings, so that the rotation of the driving shaft 6 will impart motion to the barrel 10 as will presently be more fully explained. Upon the lower end of the plunger barrel 10, a pneumatic dasher 11 is secured, having a dished form, the concave side of said dasher being lowermost and, as is usual in this class of washing machines, forces suds water down through fibrous material placed in the suds tub or box A for renovation.

In operation, assuming that soiled fibrous material along with suds water have been placed in the suds box A, and the lid closed so as to dispose the dasher 11 in position to operate upon the goods that may be gar-

ments or other household linen, the rotation of the driving shaft 6 in direction of the curved arrow α in Fig. 2 will first raise the hollow shaft or barrel 10 until the lowermost 5 tooth d^2 rides upon the pinion 8. A continuation of rotary motion given to the shaft 6 in the same direction, will rock the plunger barrel or hollow shaft 10 laterally, giving it one-fourth of a revolution, which will dis- 10 pose the roller teeth d^2 on the opposite side of the pinion 8, which latter will obviously cause a downward movement of the plunger barrel, and this operation may with ease be repeated indefinitely.

15 It is a very advantageous feature of the improvement as applied, that the pneumatic dasher 11 receives a partial revolution at each downward stroke given it, as it insures the forcing of the suds water through 20 the fibrous material in every direction.

To facilitate the operation of the washing machine, a relief valve, not shown, but that may be placed under a hood 11^a shown on the dasher 11 in Fig. 1, will admit air be- 25 neath the dasher while it is being lifted, which will reduce the labor of operating the machine.

While I have described the improvement as applied to a washing machine, I do not 30 wish to restrict its use to such a machine, as it is evident by immaterial changes, the improved mechanical movement may be utilized to actuate any machine wherein it is of advantage to give a plunger or the like 35 a vertical reciprocatory and partial rotary movement at each stroke of the machine.

Having thus described my invention, I claim as new and desire to secure by Letters Patent:

40 1. A mechanical movement, comprising a supporting frame, a rotatable driving

shaft on the frame, a pinion on an end of said shaft, a guide shaft pendent on the frame, a hollow shaft or barrel slideable and rotatable on the guide shaft, and teeth projected from the barrel and engaging the pinion.

2. A mechanical movement, comprising a supporting frame, a rotatable driving shaft on the frame, a bevel pinion on an end 50 of said shaft, a crank wheel on the other end of said shaft, a guide shaft pendent from the frame, a hollow shaft or barrel slideable and rotatable on the guide shaft, and a vertical row of teeth projected from the barrel and 55 engaging the pinion.

3. A mechanical movement, comprising a supporting frame, said frame having an upright oblong ring member, a horizontally disposed rotatable driving shaft on the frame, 60 a balance wheel having a handle and secured on one end of the driving shaft, a bevel pinion on the other end of said shaft and entering the oblong ring member of the frame, a guide shaft pendent from the frame disposed 65 near the oblong ring member, a hollow shaft on the barrel slideable and rotatable on the guide shaft, a hub on the barrel opposed to the bevel pinion, a plurality of spaced short arms projecting laterally from the hub and 70 in vertical alinement, and a like number of similar rotatable roller teeth loosely mounted on the short arms, said teeth engaging between the teeth of the bevel pinion.

In testimony whereof I have signed my 75 name to this specification in the presence of two subscribing witnesses.

ALCID OSCAR WIEGANT.
